UNITED STATES PATENT OFFICE.

REUBEN WILLIAM TARRANT, OF LONDON, ENGLAND.

RAILWAY ELECTRIC TRACK-CIRCUIT SYSTEM.

1,345,646.

Specification of Letters Patent.

Patented July 6, 1920.

Application filed November 4, 1919. Serial No. 385,697.

To all whom it may concern:

Be it known that I, REUBEN WILLIAM TARRANT, a subject of the King of Great Britain, residing at London, England, have invented new and useful Improvements in Railway Electric Track-Circuit Systems, of which the following is a specification.

This invention relates to railway electric track-circuit systems for governing the automatic actuation of traffic-controlling apparatus, and has for its object to provide means for enabling continuous electric current, normally flowing in a track-circuit, to be automatically converted into pulsating current, when the value of the continuous current exceeds a predetermined limit, as the result (for example) of the resistance between the rails of the track-section being reduced below a predetermined value.

For this purpose it has already been proposed to employ at the battery end of the track-circuit (*i. e.* the end remote from the usual traffic-controlling track-relay) what may be termed an electromagnetic interrupter or pulsator, comprising a switch and an electromagnet for controlling the same, whereof both the switch and the winding of the electromagnet are interposed in series in the track-circuit; the armature of the electromagnet serving to actuate the switch-blade in such manner that the switch, normally held closed, will be momentarily opened under the increased attractive effort exerted upon the armature when the current-output of the battery rises beyond a predetermined value in consequence of the resistance between the rails being reduced below a predetermined limit as the result, for example, of the ballast and sleepers becoming wetted by rain, or of a vehicle entering the track-section and thus short-circuiting the battery. The opening of the switch momentarily breaks the track-circuit, or reduces the value of the current flowing therein, so that the switch is immediately re-closed, with the result that the same cycle of operations is repeated as long as the reduction in the resistance between the rails continues; the pulsator-armature and switch vibrating meanwhile and the normally-continuous current in the track-circuit being converted for the time being into a rapidly-pulsating current as a result of the making and breaking of the circuit.

According to the present invention the

pulsator-armature is in the form of a stiff vibratory reed which constitutes also the switch, and which is suitably polarized so as to cause the attractive effort exerted by the electromagnet to be modified (*i. e.* either reinforced, or partially counteracted) as may be found desirable. Such reinforcement may be obtained by making the armature-reed mechanically and magnetically integral with the core of the pulsator-coil; while either reinforcement or counteraction may be obtained by correspondingly arranging the winding of a relatively high-resistance coil encircling the armature-reed and interposed in a permanently-closed connection between a pole of the track-circuit battery and the end of one of the track-rails. The latter arrangement serves also to prevent complete severance of the track-circuit, and the occurrence of sparking, when the switch is opened; sparking being also preventable by other means, such as the use of a condenser interposed in a separate connection which may be either substituted for, or provided in parallel with, the armature-polarizing circuit. The armature-reed should be sufficiently stiff to be free from liability to oscillate (so as to break the circuit which is normally closed) under the influence of the strongest mechanical vibrations to which it may be exposed in consequence, for example, of the passage of trains over the track.

In the accompanying drawings, Figures 1, 2, 3 and 4 illustrate, in each case diagrammatically, four typical examples of the application of the invention; similar reference symbols denoting corresponding parts in all the figures.

In each case, A and B are the respective track-rails, C is the track-circuit battery, and D the usual traffic-controlling track-relay, while E is the electromagnetic pulsator of the present invention; this pulsator comprising an electromagnet F and a switch G in the form of a stiff vibratory reed which constitutes the armature of the electromagnet. The reed-switch G, which is shown as mechanically and magnetically integral with the electromagnet-core, extends from that end f^1 of the core of the magnet F to which it is permanently fixed, beyond the opposite or polar extremity f^2 of the magnet-core so as to be subject to the attractive effort exerted thereat; the free end of the switch G normally resting by its own elasticity against a contact h so as to be free to move toward the

pole f^2 of the magnet. It is obvious that the reed instead of constituting the switch may actuate a switch.

Referring now to Figs. 1 and 2, it will be seen that in each of these the opposite ends of the winding f of the electromagnet F are permanently connected, respectively, to the adjacent end of the rail A and to one pole of the battery C, the opposite pole of the battery being permanently connected to the fixed end of the reed-switch G (or to the contiguous end f^1 of the core of the magnet F); while the resting-contact h of the switch G is permanently connected to the adjacent end of the rail B. So long as the current-output from the battery G is of the normal working value, the attractive effort exerted by the electromagnet F is insufficient to disturb the reed-switch G from its resting-contact h , so that the current in the track-circuit remains constant and continuous, and the reed G does not vibrate. When, however, the inter-rail resistance falls below a predetermined limit, owing to (say) the presence of a train in the track-section of the ballast and sleepers being wet, the current output of the battery C will increase so far as to permit the attractive effort exerted by the electromagnet F to raise the switch G momentarily from its resting-contact h . This has for effect to momentarily break the track-circuit or reduce the value of the current therein, so that the switch G at once returns to its resting-contact h ; the same cycle of operations being repeated as long as the inter-rail resistance remains below the predetermined value, so that the reed-switch G continues to vibrate and the continuous battery-current is converted for the time being into a rapidly-pulsating current.

In Fig. 1, the occurrence of sparking at the resting-contact h , is prevented by the interposition of a condenser j , in a bridge-connection between the contact h and the connection from the battery C to the reed-switch G. In Fig. 2, the same result is obtained by the similar interposition of a relatively high-resistance winding g , coiled about the armature G, this winding g being employed either in place of or in addition to the condenser j , which latter is shown in dotted lines in Fig. 2. The fact of the armature-reed G being, as in all the samples illustrated, magnetically integral with the core of the electromagnet F, causes it to be polarized so that the attractive effort exerted upon it is reinforced. This reinforcement may be either increased or diminished by the use of the winding g , which thus affords means for enabling the coming into action of the pulsator to be adjusted as may be found necessary.

Referring now to Figs. 3 and 4, it will be seen that the arrangements therein illus-

trated differ from those shown in Figs. 1 and 2, respectively, only in the following particulars. In Figs. 3 and 4, while one end of the winding f , of the electromagnet F is permanently connected to one pole of the battery C, the opposite end of this winding is permanently connected to the fixed end of the reed-switch G (or to the contiguous end f^1 of the magnet F); the opposite pole of the battery C being permanently connected to the adjacent end of the rail B, and the resting-contact h being permanently connected to the adjacent end of the rail A. In Fig. 3, sparking is prevented by the interposition of a condenser j in a bridge-connection between the resting contact h and the connection from the winding f to the reed-switch G, while in Fig. 4, the same result is obtained by the similar interposition of a relatively high-resistance winding g , coiled about the armature G, this winding being employed either in place of or in addition to the condenser j , which latter is shown in dotted lines in Fig. 4. The action of the arrangements shown in Figs. 3 and 4 is similar to that of the arrangements shown in Figs. 1 and 2.

The invention enables several advantages to be obtained. Thus for example, it is well known that, on a vehicle entering a track-section unprovided with special current-economizing means, the short-circuiting of the track-circuit battery (consequent on the virtual cutting-out of the track-relay by the "train-shunt") causes so great an increase in current-consumption that serious waste occurs in the event of the track-section remaining occupied for a considerable period. The present invention, however, provides in effect an automatic current-economizer serving to reduce the current-consumption throughout the entire period during which the track-section is occupied, for the reason that the conversion of the normally-continuous current into a pulsating current is equivalent to the introduction of a resistance into the track-circuit, so that the rate of current-consumption when the track-section is occupied will never exceed, and can even be made less than, the rate normally prevailing when the track-section is empty.

The reduction of current, which thus automatically follows on a reduction of the inter-rail resistance below a predetermined limit, also secures the "falling-away" of the armature d of the track-relay D (Figs. 1 to 4) occurring with greater certainty at the required moment, for the reason that the train-shunt not only reduces the current flowing in the track-relay coils (as is usual), but also increases the current through the pulsator-coil f , whose energization breaks the battery-circuit at h ; this feature, which tends to prevent intermittent "picking-up" of the track-relay armature d in the event

of wide variations occurring in the value of the current flowing in the train-shunt, remaining unaffected so long as such current-value is sufficiently high to cause the reed-switch G to vibrate. Nevertheless, the efficiency of the continuous-current track-relay D is not diminished, for the reason that, under normal conditions (*i. e.* so long as the track-section is unoccupied or the inter-rail resistance does not fall below the predetermined limit), the current energizing the track-relay always remains continuous current.

The pulsator E may be adjusted to produce pulsations, in the current flowing in the track-circuit, at any current-value above that required to cause the track-relay armature d to fall away; but the pulsator will not come into operation until the current through the track-circuit battery C has attained the predetermined value; hence, when the inter-rail resistance falls abnormally owing to some cause (such as rain on the permanent way) other than the presence of a vehicle in the track-section, the pulsator E will produce pulsations in the track-circuit, and thus reduce the current flowing therein, but not necessarily to such an extent as to cause the track-relay armature d to fall away. In this sense, therefore, the pulsator E constitutes in effect an automatic regulating-resistance, or constantly-acting economizer, governing the value of the current which is permitted to flow from the track-circuit battery C into the track-circuit.

Having now particularly described and ascertained the nature of my said invention and the manner in which the same is to be performed, I declare that what I claim is:

1. In a railway electric track-circuit which includes on the one hand the winding of a traffic-controlling relay interposed in series between the track-rails at one end of a track-section and on the other hand a source of continuous current, an electromagnet winding, and a normally-closed switch controlled thereby, all interposed in series between the track-rails at the opposite end of the track-section, the combination of a core for said electromagnet winding, and an armature therefor formed by a vibratory reed which is mechanically and magnetically integral with said core and which also constitutes said switch; substantially as and for the purpose set forth.

2. In a railway electric track-circuit which includes on the one hand the winding of a traffic-controlling relay interposed in series between the track-rails at one end of a track-section, and on the other hand a source of continuous current, an electromagnet winding, and a normally-closed switch controlled thereby, all interposed in

series between the track-rails at the opposite end of the track-section; the combination of a core for said electromagnet winding, an armature therefor formed by a vibratory reed which is mechanically and magnetically integral with said core and which also constitutes said switch, and a relatively high-resistance winding coiled about said armature and interposed in a permanently closed connection between the track rails at the last-mentioned end of the track-section, said connection including the source of current and the electromagnet winding, but not the switch; substantially as and for the purpose set forth.

3. In a railway electric track-circuit which includes on the one hand the winding of a traffic-controlling relay interposed in series between the track-rails at one end of a track-section, and on the other hand a source of continuous current, an electromagnet winding, and a normally-closed switch controlled thereby, all interposed in series between the track-rails at the opposite end of the track-section; the combination of a core for said electromagnet winding, an armature therefor formed by a vibratory reed which is mechanically and magnetically integral with said core and which also constitutes said switch, and a condenser interposed in a connection in parallel with that connection which is normally bridged by the switch; substantially as and for the purpose set forth.

4. In a railway electric track-circuit which includes on the one hand the winding of a traffic-controlling relay interposed in series between the track-rails at one end of a track-section, and on the other hand a source of continuous current, an electromagnet winding, and a normally-closed switch controlled thereby, all interposed in series between the track-rails at the opposite end of a track-section; the combination of a core for said electromagnet winding, an armature therefor formed by a vibratory reed which is mechanically and magnetically integral with said core and which also constitutes said switch, a condenser, and a relatively high-resistance winding coiled about said armature, said condenser and high-resistance winding being interposed in connections both of which are in parallel with that connection which is normally bridged by the switch; substantially as and for the purpose set forth.

5. In a railway electric track-circuit which includes on the one hand the winding of a traffic-controlling relay interposed in series between the track-rails at one end of a track-section, and on the other hand a source of continuous current and an electromagnet winding both interposed in series between the track-rails at the opposite end of the track-section; the combination of a

core for said electromagnet winding and constituting therewith an electromagnet, a normally-closed switch controlled by said electromagnet and interposed in series therewith and with the source of current between the track-rails at the last-mentioned end of the track-section, said switch constituting an armature for said electromagnet, and a relatively high-resistance winding coiled

about said switch and interposed in a permanently closed connection between the track-rails at said last-mentioned end of the track-section, said permanently closed connection including the source of current and the electromagnet winding; but not the switch; substantially as and for the purpose set forth.

REUBEN WILLIAM TARRANT.
